DESIGN FOR A CONDIMENT CONTAINER

William Johnson, Hazel Park, Mich., and Elno H. Trump, Barberton, Ohio, assignors to Ward Plastic and Rubber Company, Detroit, Mich., a corporation of Michigan

Application March 20, 1940, Serial No. 91,088

Term of patent 7 years

To all whom it may concern:

Be it known that we, William Johnson and Elno H. Trump, citizens of the United States, residing at Hazel Park, county of Oakland, and State of Michigan, and Barberton, county of Summit, and State of Ohio, respectively, have invented a new, original, and ornamental Design for a Condiment Container, of which the following is a specification, reference being made to the accompanying drawing, forming part thereof.

Fig. 1 is a front perspective view of a condiment container, showing our new design;

Fig. 2 is a side elevational view;
Fig. 3 is a rear elevational view; and
Fig. 4 is a top plan view thereof.

The heavy shading on the base and handle indicates a contrasting color.

We claim:

The ornamental design for a condiment container, as shown and described.

WILLIAM JOHNSON.
ELNO H. TRUMP.
